UNITED STATES PATENT OFFICE.

MAE DORRANCE, OF SMITHFIELD, OHIO.

HOSPITAL PAD OR CUSHION.

Application filed June 8, 1921. Serial No. 475,899.

To all whom it may concern:

Be it known that I, MAE DORRANCE, a citizen of the United States of America, and resident of Smithfield, county of Jefferson, 5 and State of Ohio, have invented certain new and useful Improvements in Hospital Pads or Cushions, of which the following is a specification.

This invention relates broadly to pneumatic cushions or pads, and it has for its primary object to provide a pad or cushion of this type adapted for home and hospital use and designed to serve not only as a cushion, but also as a receptacle for fluids, and 15 provided with means whereby the fluids may be drained therefrom.

A further object is to provide an inflatable pad which shall constitute, in addition to a supporting cushion upon which a patient 20 or invalid may rest with more than usual comfort, a device possessing some of the characteristics of a bed pan.

In describing the invention in detail, reference is herein had to the accompanying 25 drawings, in which—

Figure 1 is a top plan view of the invention; and—

Figure 2 is a section on line 2—2, Fig. 1.

Referring to said drawings, 1 indicates 30 a flat base of flexible material, preferably rubber, and superimposed upon said base are two inflatable tubular rings 2 and 3 having a substantially concentric disposition and possessing a form which is semi-cylindrical in cross section. Said base, which is integral with said rings, is made of such relatively heavier and inelastic material 35 than the rings that, when the latter are fully inflated, the base retains its flat, or a substantially flat, form.

The inner ring 3 is substantially circular in form, while the outer ring 2 is of oblong oval form, being elongated and tapered in one direction to materially increase in said 45 direction the relative width of the space between said rings, said outer ring thus being made to conform to the part of the patient's body which is to rest upon the cushion.

The pad or cushion described preferably 50 has an outside diameter considerably in excess of that of the hospital cushions or pads which hitherto have been commonly employed; and, therefore, the inner ring 3 is provided as a support supplemental to that 55 afforded by the ring 2.

The channel 4 formed between the rings 2 and 3 constitutes a receptacle for fluids which drain from the body of a patient resting upon the cushion, as does also the space 5 enclosed by the inner ring 3. Drainage outlets of any suitable form, as nipples 6 adapted for having drain tubes 7 attached thereto, are provided in the base 1 at suitable points, as shown.

An inflation valve 8 is provided in the outer ring 2 at a suitable point, and a similar valve may also be provided in the ring 3, but it is preferred that a connecting passageway 9 be provided between said rings so that both may be simultaneously inflated 60 by the use of the single valve 8.

Since the cushion has a flat base adapted to rest more or less closely throughout upon the bed or mattress, it is manifest that the tendency to shift, which is inherent in ordinary forms of cushions comprising tubes of cylindrical cross section, is largely obviated, thus in large measure contributing to the comfort of the patient. Furthermore, due to the provision of the receptacle-like enclosures 4 and 5, soiling of the mattress is 70 largely prevented.

What is claimed is—

1. A rubber pad comprising a flat base, a plurality of substantially concentric inflatable body-cushioning rings superimposed on said base and integral with the latter, said base being relatively inelastic, a radial communicating passageway between said rings, and drainage nipples fixed in said base in the spaces enclosed by said rings.

2. A hospital pad comprising a flat base, two inflatable body-cushioning rings superimposed on said base, the inner of said rings being substantially circular in form and the outer of said rings having its major portion located concentrically with respect to said inner ring and being elongated and tapered in one direction whereby the relative width of the space between said rings is 95 materially increased in said direction, and means affording drainage for the spaces enclosed by said rings.

In testimony whereof, I affix my signature in presence of two subscribing witnesses.

MAE DORRANCE.
